UNITED STATES PATENT OFFICE

2,474,361

ELECTRIC WATER HEATER

Paul C. Jones, Nichols, S. C.

Application November 29, 1946, Serial No. 712,806

2 Claims. (Cl. 219—39)

1

This invention relates to electric water heaters, and more particularly of a type adapted to be installed with an ordinary coal and water heating system to serve as an auxiliary and to be used during the summertime when the coal stove is not in operation, and at times when only a small quantity of hot water is desired within a short duration or be installed directly to the hot water tank without the coal stove.

It is an object of the present invention to provide an electric heater which is adapted to be installed in a water heating system of a coal stove with little difficulty or used separately and adapted when in use to provide a small amount of hot water upon short notice.

It is another object of the invention to provide an electric heating element construction adapted to be confined within a small narrow tube and be insulated therefrom and also to provide between the heating coils throughout the length of the tube an insulation for maintaining them separate from one another and wherein little space is consumed by the insulation and the heating coils so that the passage of water through the pipe is not interfered with and wherein the unit may be left in the installation at all times, even though the electric heater is not in use.

For other objects, and for a better understanding of the invention, reference may be had to the following detailed description taken in connection with the accompanying drawings, in which:

Figure 1 is a fragmentary view of the upper portion of the electric heater installation and showing the faucet from which the hot water is drained when supplied from the electric heater arrangement.

Figure 2 is a transverse sectional view taken on line 2—2 of Figure 1, and looking in the direction of the arrows thereof.

Figure 3 is an enlarged cross-sectional view taken through one of the terminal connections of the heating elements and as viewed on line 3—3 of Figure 1, and looking in the direction of the arrows thereof.

Figure 4 is an elevational view of the electric heater installation with portions broken away and shown in cross-section, but with the section being taken through a plane at right angles to the plane through which the section of Figure 1 has been taken.

Figure 5 is an elevational view of the heating system showing a hot water tank connected with a stove and with the electric heater auxiliary con-

2

nected into the pipe line from the stove to the tank.

Referring now particularly to Figure 5, there is shown a hot water system including a boiler 10, a stove 11, and an electric heater 12 disposed in the outlet pipe 13 from the stove and embodying the features of the present invention. Water is delivered to the stove from the hot water tank 10 through an inlet pipe 14 taken from the bottom of the boiler, and after passing through the heating coils of the stove will pass upwardly through the outlet pipe and the electric heater 12. A chimney 15 extends upwardly from the stove to take off the smoke generated in the stove from coal or wood which has been fired within the same. At the top of the boiler 10 are outlet and return pipes 16 and 17 for delivering and returning hot water from and to the boiler.

Referring now particularly to Figures 1 to 4, 20 description will be made of the auxiliary electric heater 12. This heater is included within a tube or pipe 21. The pipe houses an insulating sleeve 22 containing a heating element 23 which extends down one side of an asbestos insulating member 24 centrally disposed within the tube 22 and then passes upwardly on the opposite side of the asbestos member 24 to the top of the tube or sleeve 22. The lower end of the pipe 21 is threaded into a reducing coupling 25 threaded upon an outlet pipe 13. The upper end of the pipe 21 has a T-fitting 26 connected to it from which there extends a spigot or faucet 27. To the upper end of the fitting there is connected a coupling 28 for the attachment thereto of a pipe 29. On 35 opposite sides of the T-fitting are terminal members 31 and 32 extending from the interior of the fitting to the exterior thereof for the attachment thereto of current supply wires 33 and 34 which may be connected to any source of current supply.

Each terminal member 31 or 32 is surrounded by a spool-like insulation element 35 which is extended through an opening 36 in the T-fitting 26. This terminal is made secure upon the insulation element 35 by a nut 37, and the wire is 45 in turn made secure on the terminal by a washer 38 and a nut 39. The end of the heater element is connected to the inner end of the terminal 31 between two washers 41 and 42, the latter of which abuts with a head formation 43 on the 50 end of the terminal element 31.

At times during the summer months when the stove 11 is not in operation, and it is desired to obtain in a short time a small quantity of water, the electric current is turned on by making 55 the connection of the wires 33 and 34 with an elec-

tric source, and with an arrangement such as I have shown I have been able to obtain a pint of hot water within ninety seconds from the time the current has been turned on, and thus enough water to shave with. Since the asbestos central strip 24 extends the full length of the pipe 21, good insulation is effected and at times when there is no water in the tube, the heater element 23 will be supported against collapse or any tendency of the same to fill the tube and cause the same to be obstructed. The amount of space taken up by the heater element 23 and the asbestos strip 24 is negligible and will not at any time interfere with the operation of the hot water system such as when dependency is made upon the stove for the hot water being delivered to the tank 10. If desired, the electric heater can be used along with the stove when the stove is in operation, and when it is desired to build up the water supply in the tank quickly, but preferably the electric heater installation is utilized for obtaining small quantities of hot water at times when the stove is not being used.

This heater can be installed in connection with an ordinary coal water heater, or installed directly to a hot water tank, independent of any coal heater. It will furnish enough hot water when used alone continuously from tank for all ordinary purposes, including bathtub. By the faucet at top of heater, a small amount of hot water can be obtained almost instantly. Closing this faucet allows hot water to enter tank and is stored up to be drawn through pipe 16.

Having now described my invention, I claim:

1. An electric heater installation for a hot water supply system including a hot water tank and a stove and adapted to produce small quantities of hot water within a short time and independently of the hot water tank comprising a large tube having fittings upon the opposite ends adapted to be disposed between sections of the outlet pipe of said stove which normally heats the hot water for said tank, a valve-controlled outlet fitting at one end of the tube for removing the hot water generated within the installation, terminal elements extending through the outlet fitting and insulated therefrom, a heating element extending downwardly from one of the terminals throughout the extent of the tube and thence upwardly throughout the tube for connection with the other terminal, said fitting

at the outlet end of the tube being a T-fitting, and a spigot connected to said fitting, said terminal elements being connected to the opposite sides of said fitting.

5 2. An electric heater installation for a hot water supply system including a hot water tank and a stove and adapted to produce small quantities of hot water within a short time and independently of the hot water tank comprising a large tube having fittings upon the opposite ends adapted to be disposed between sections of the outlet pipe of said stove which normally heats the hot water for said tank, a valve-controlled outlet fitting at one end of the tube for removing the hot water generated within the installation, terminal elements extending through the outlet fitting and insulated therefrom, a heating element extending downwardly from one of the terminals throughout the extent of the tube and thence upwardly throughout the tube for connection with the other terminal, an insulating strip extending downwardly throughout the tube and between the downwardly extending and upwardly extending portions of the heater element, said fitting at the outlet end of the pipe being a T-fitting, a spigot connected to the T-fitting, said terminals being connected to opposite sides of the T-fitting, and the insulating strip extending upwardly into the T-fitting and between the terminals, and an insulating sleeve surrounding the heating element and the insulating strip and filling the pipe containing the same.

PAUL C. JONES.
